(57) CLAIM

The ornamental design for a raised cricket cage holder, as shown and described.

DESCRIPTION

FIG. 1 is a front elevation view of a raised cricket cage holder, showing my new design;

FIG. 2 is a right side elevation view thereof;

FIG. 3 is a left side elevation view thereof;

FIG. 4 is a top plan view thereof;

FIG. 5 is a perspective view from below thereof; and,

FIG. 6 is a perspective view from above thereof.

The broken lines in the drawings depict unclaimed portions of the raised cricket cage holder and form no part of the claimed design.

1 Claim, 2 Drawing Sheets(56)
